UNITED STATES PATENT OFFICE.

EDMOND H. HOFFMANN, OF NEWARK, NEW JERSEY, ASSIGNOR OF ONE-HALF TO JABEZ FEAREY, OF SAME PLACE.

ELECTRICAL CONDUIT AND DISCHARGER.

SPECIFICATION forming part of Letters Patent No. 320,253, dated June 16, 1885.

Application filed June 7, 1884. (No model.)

To all whom it may concern:

Be it known that I, EDMOND H. HOFFMANN, a citizen of the United States, residing in Newark, Essex county, New Jersey, have invented 5 certain new and useful Improvements in Electrical Conduits and Dischargers, fully described and represented in the following specification and the accompanying drawings, forming a part of the same.

10 This invention consists in a conduit provided with man-hole chambers having a series of conductors arranged therein, and provided with fastenings or posts for the attachment of line-wires when the same are inserted 15 in the conduit from time to time, the said conductors being provided with a discharging-wire arranged parallel thereto and connected with the ground for relieving such connected line-wires of induced currents.

20 In the drawings, Figure 1 is a plan of the conduit, with a man-hole at each end, the roof of the conduit and man-hole being removed to show the interior construction. Fig. 2 is a vertical central longitudinal section of the same 25 parts. Fig. 3 is a section of one of the service-outlets, enlarged, with the adjacent wall of the conduit. Fig. 4 is a side view of the discharging device, and Fig. 5 is a transverse section of the same. Fig. 6 is a perspective view 30 of the conduit-trough, and Fig. 7 a similar view of the cover or roof for the same; and Fig. 8 is a vertical section of a conduit and man-hole with a hollow post attached, the lower part only of the post being in section and 35 being broken off to indicate that the height shown is indefinite.

A is the body of the conduit, formed of baked terra-cotta, made in section of a few feet in length, and formed as an open trough, 40 with ledges *a* upon its sides to receive the wheels *a'* of a carriage, B. The ledges are preferably provided with a bar of metal to serve as a veil and to cover the joints of the sections, a groove, *c*, being formed in the ledge for such purpose, 45 and the veil *c* being merely a large galvanized iron wire cemented in its place with a resinous compound. The carriage extends across the width of the conduit, and is provided with a horizontal series of hooks or binding-posts, 50 *e*, at each end, so that the conducting-wires

may be attached to the carriage at different points in the width of the conduit and laid along its bottom at any parts of its width when the carriage is drawn through the conduit.

55

C is the cover of the conduit, made of terra-cotta in sections like the body, and may be cemented tightly to the trough and the joints covered with hydraulic cement to exclude water. The edges of the cover at C are also made 60 to hook over the sides of the trough, so as to shed water, and is preferably pitched at the center for the same reason as at C².

To make service-connections readily, and to avoid breaking through the terra-cotta after 65 the conduit is laid, metallic outlets or plates D are bolted into the sides of the trough, or are cemented into openings prepared for such purpose. Fig. 3 shows a double plate with grooved edges, which can be applied to a suitable opening in the terra-cotta and clamped thereto by bolts or rivets *d*; and also a single plate fastened into a recess in the side of the trough A by cement *d'*. The plates are in any case provided with a nozzle and screw-cap, or 70 with a threaded socket to fit a service-pipe, which socket would be closed by a screw-plug, D', as in Fig. 3, until the connection would be required.

E are chambers placed along the conduit 75 at intervals, and provided with man-holes F F, through which the chambers can be entered to insert the conductors in the conduit.

G is a coil of line-wire hung in the man-hole, and H H are drums in the chambers at the opposite ends of a given conduit, provided with cranks *h* to wind up a cable or rope, *g*, attached to the carriage B.

I is the frame of the discharging apparatus, which is shown as of open rectangular structure, but may be made of a flat board or bed-plate, if preferred, its essential parts being a series of separate naked parallel conductors, J, insulated from the earth, and provided with means for connecting the coated line-wires at 90 their opposite ends, and in a discharging-wire, J', traversed back and forth between the said conductors and then led to the ground, as shown in Fig. 4. The conductors J and discharging wire or brushes J' may therefore be 95 100

stretched between insulated fixed points upon a flat bed-plate, and such equivalent is claimed herein where the term "frame" is used.

The wire J' is preferably formed like a bottle-cleaning or flue-cleaning brush, with a succession of radial points adapted to draw the accumulated or static electricity from the wires J and to conduct it to the ground, as by wire L . The wires J are of naked metal, while the line-wires K , electrically connected with them, are provided with insulated coatings, like all wires laid in conduit in close proximity. Such insulated coatings occasion and prevent the free discharge of the induced electricity, for which reason I interpose the naked wires J in the circuit, and discharge the electricity therefrom by the earth-connection at J' and L .

The conductors J are shown provided with binding-posts $l' l'$ at each end, so that the current of any line may be led through it when any of the said conductors is placed in the circuit of such line. Each conductor J may be placed in the circuit of a different line, and the single discharging-brush wire J' serve to remove static or induced electricity from them all.

The construction described is operated as follows: After the building of man-holes or chambers at proper intervals, the terra-cotta trough is laid to connect the chambers and the rails cemented in the grooves in the ledges a . The carriage is then put in the conduit, the drums H and cables g are cemented therewith, and the discharging device fitted into the chamber at any convenient point upon the side or bottom. The cover C is then laid upon the conduit and secured permanently, and a reel of line-wire, G , provided at both of the man-holes. Two men, located in two adjacent chambers, can then readily draw the carriage back and forth and lay the line-wire K at any point upon the width of the conduit's bottom by first attaching the line from the reel to the hook e upon the carriage over such point. When the desired number of lines have been laid in such conduit, their ends would be connected to the posts l at the nearer ends of the conductors J in the discharging device, and the continuation of such lines would thereafter be made by connection with the opposite ends of the conductors J at the posts l' .

The lines could be laid in all the parts of the conduit in similar manner and continuous connection for each distinct line be made through as many of the discharging devices as might prove needful to prevent all effect of the induced electricity upon the instruments connected with the lines.

It will be observed that the construction of the discharging device includes sections of conductors arranged in the proper relation to the discharging or ground wire, and that such sections are provided with clamps or posts $l l'$ at both ends, so as to be connected with any particular circuit in the most convenient and

expeditious manner. Such construction, therefore, secures more perfect results than when a discharging-wire is laid with the line-wires in the closed conduit in some imperfect manner, as the frame may be constructed by skilled workmen with needful care and the line-wires connected to it afterward without any skill whatever.

Such frame may be applied to a series of line-wires at any point in their circuit, as when they are led into an operating-room, or at other convenient points, and furnishes an exceedingly compact and effective means of exposing a large number of conductors to the action of one or more discharging-wires. The frame may also be used where the line-wires pass out of the operating-room to divert any extraneous induced currents to the earth, and thus prevent them from affecting adjoining wires.

The effect would obviously be the same in principle if two or more of the wires J' were extended across the frame, and in such case they may be each confined to one part of the frame and operate upon different conductors, or be stretched upon opposite sides of the same conductors.

The series of conductors and discharging-wires may be made of any desired length and be provided with any ordinary means of attaching the line-wires at the opposite ends, $l l'$, provided the structure includes the arrangement shown and such means of connection. I have also shown herein a means for diverting a series of line-wires from a subterranean conduit to a series of poles above ground, which consists in the application of a hollow pole to some point above the conduit, and in suitable apertures near the head of the pole, through which the wires can be extended to the insulators upon the poles, and thence to other ordinary poles or supports.

In Fig. 8, A is the conduit. n is an outlet, from which the wires K are conducted to the foot of the pole P and through its interior to the apertures r , near the cross-bar R , to which the insulators s are secured. This construction secures complete protection for the wires from the conduit to the top of the pole, as the pole may be extended downward to the conduit, or equivalent tubing, as T , be applied to the wires where they pass through the soil. The pole is preferably made of iron tube, and may be made in sections coupled together in any convenient manner.

The material for the conduit described herein is intended to be of terra-cotta or other earthy material capable of moulding into sections of the desired form and hardening so as to bear handling, like certain kinds of water-pipes made of sand and hydraulic cement. Such materials are much cheaper than iron, and, as they are not affected electrically, are much more suitable in every way than metal for the purpose described. When made of the earthy

materials, I claim the inner side of the conduit may be coated with an insulating composition or not, as preferred

What I claim, and desire to secure by Letters Patent herein, is—

- 5 1. The combination, with an electrical conduit and a series of line-wires therein, of a discharging device consisting of a frame containing a series of parallel conductors, clamps or posts at each end of such conductors, and a discharging-wire traversed back and forth between such conductors and connected with the ground, substantially as and for the purpose set forth.
- 10 15 2. The combination, with a conduit adapted

to receive a series of electrical line-wires, of man-hole chambers provided with an induction discharging device having a series of separate insulated conductors provided with binding-posts at their extremities, to receive and 20 to extend such line-wires, substantially in the manner herein shown and described.

In testimony whereof I have hereunto set my hand in the presence of two subscribing witnesses.

EDMOND H. HOFFMANN.
